Primary Examiner — Lakiya Rogers*Assistant Examiner* — Carissa C Fitts(74) *Attorney, Agent, or Firm* — Weiss & Arons LLP; Avi Goldenberg, Esq.(57) **CLAIM**

The ornamental design for a flashlight, as shown and described.

DESCRIPTION

FIG. 1 is a top, front, right perspective view of a flashlight showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of the environment is for illustrative purposes only and forms no part of the claimed design.
